COMBINATION BED AND CHAIR

Hyman Gertler, Montreal, Quebec, Canada

Application August 29, 1939, Serial No. 292,481

2 Claims. (Cl. 155—48)

The present invention relates to a combination bed and chair.

It has previously been proposed to provide such articles having the whole of the bed forming parts, in their folded condition, disposed in the seat position of the chair whereby a bulky structure is provided in which only one of those parts serves a useful purpose as a chair.

According to another proposal the back of the chair was removable so as to form a part of the bed. In either of these previous proposals it is apparent that a number of supporting members and catch members would be required for retaining the various parts in the appropriate places, and furthermore since the bed forming parts were of the same size the joints or hinges between such parts were so positioned as to cause discomfort to the user by the presence of hard and unsprung portions for instance near the user's hips.

It is an object of this invention to provide a combination bed and chair of simple yet sturdy construction in which catch members and the like are not required for retaining the various parts in position, and which is comfortable in use as either a bed or chair.

According to the present invention therefore there is provided a combination bed and chair having a frame the front portion of which is split and hinged, each of the parts thereof having attached thereto one of two equal sized bed forming sections, which in the folded position form the chair seat, and a smaller head section hingedly attached to the upper of said two sections, the dimensions of the sections being such that when in use as a bed the hinged parts will be situated approximately at the knees and neck of the user.

It will thus be possible to provide a combination bed and chair comfortable in both of its uses. Suitable cushions for the seat and back may be provided and the back cushion may if desired be supported partially by the back of the chair and partially by the head section in its folded position, wherein it may be disposed at a small angle to the back of the chair.

A preferred embodiment of the invention will now be described by way of example only with reference to the accompanying drawing in which—

Fig. 1 shows a side elevation partially in section of the device as a chair.

Fig. 2 shows a side elevation partially in section of the device used as a bed and

Fig. 3 is a plan view of Fig. 2.

The combination bed and chair has a frame 55

10 having front and back legs 1 and 2, a back indicated generally by 3, and arm rest portions 4. The front member 5 of the frame 10 is formed in two sections hinged together at 11 each part thereof having secured thereto a bed frame, for instance of cast iron, which two frames 12 and 13 are of equal size and have any desired form of springing therein as shown in Fig. 3.

Hingedly attached to the end of the frame 13 is a smaller head section 14 having hinged thereto legs 15 to support one end of the bed.

The back 3 of the chair frame has a cross bar 16, a panel 19 extending beneath it and vertically extending bars 6 from the top of the back to the cross bar 16. The frame so constructed is proportioned so that when the combination article is used as a chair the folded frames 12 and 13 and head section 14 lie strictly within the normal confines of the chair.

When the combination article is used as a bed it will be seen from Figures 2 and 3 that the parts 12, 13 and 14 are unfolded and are supported on the legs 1 and 2, and the legs 15, and it will be seen that by using the section 14 as the head of the bed, the hinged parts which will necessarily be harder to lie on than the spring parts will be situated approximately at the neck and knees of the user thus avoiding the discomfort previously experienced with beds of this kind.

When the article is folded for use as a chair, it will be seen that the frame 13 is disposed above the frame 12 within the chair frame 10. The legs 15 are folded into the frame of the head section 14 which is itself angularly displaced about its hinges with respect to the frame 13, so that in the chair position it rests against the cross bar 16 at a small angle thereto, and thus affords a support and guide for the head cushion 18 to dispose it at a natural angle of repose. This support together with that provided by the back of the chair frame enables the cushion to be kept in a comfortable position for the user and functions to prevent the head cushion from wedging between the seat cushions and the back of the frame.

On the seat of the chair two cushions 17 are provided which for convenience are attached together so that they may easily be used, with the separate head cushion 18 as a mattress for the bed. It may further be noted that in a preferred embodiment the springing in the head section 14 is arranged at right angles to that in the two main sections 12 and 13, so as to increase the comfort of the head section. Furthermore the hinges of the front frame 5 and the attachment

of the two sections 12, 13 to the respective parts thereof is so arranged that the two sections, and the two parts will be substantially flush with each other so as to avoid an uneven surface.

What I claim as my invention is:

1. A combination bed and chair comprising in combination a chair frame having a front portion formed in two sections and hinged together, two bed forming sections of equal size each attached to one of said hinged front sections and in folded position forming the base of the chair seat, a smaller head section hingedly attached to the upper of said two sections and designed to be co-extensive with the upper section when said upper section and head section are unfolded to form the base of a bed, the head section having foldable supporting means to maintain it and the upper section in a plane parallel to the lower section in bed forming position, the dimensions of the sections being such that when in use as a bed, the hinged connections between the sections will be situated approximately at the neck and knees of the user and when folded will lie within the normal confines of the chair, said head section being hingedly connected to the upper section at a point inwardly of the end of said section nearest said connection to dispose the head section at an incline to the back portion of the frame, a pair of cushions forming a seat and supported by the base and a cushion of smaller dimensions designed to rest on the uppermost seat cushion and lie against the back of the frame, the upper portion of the inclined head section forming a guide to dispose the smaller cushion at a natural angle of repose and to pre-

vent said cushion from wedging between the seat cushions and the back of the frame.

2. A combination bed and chair consisting of a plurality of parts capable of constituting without addition or subtraction a complete bed and mattress or a complete upholstered chair comprising a chair frame having a front portion formed in two sections and hinged together, two bed forming sections of equal size each attached to one of said hinged front sections and in folded position forming the base of the chair seat, a smaller head section hingedly attached to the upper of said two sections and designed to be co-extensive with the upper section when said upper section and head section are unfolded to form the base of a bed, the head section having foldable supporting means to maintain it and the upper section in a plane parallel to the lower section in bed forming position, a pair of cushions adapted to fit the two bed forming sections and when folded to form a seat supported by the base of the chair, a smaller cushion adapted to fit the head section and when folded to rest on the uppermost seat cushion and lie against the back of the frame, the head section when folded being disposed to lie at an incline to the back portion of the frame forming a guide to dispose the smaller cushion at a natural angle of repose and to prevent said cushion from wedging between the seat cushions and the back of the frame, the dimensions of the sections and cushions being such that when folded they will lie within the normal confines of the chair.

HYMAN GERTLER.
